UNITED STATES PATENT OFFICE.

IGNAZ SCHWINN, OF CHICAGO, ILLINOIS.

DESIGN FOR A BICYCLE-FRAME.

52,150.

Specification for Design.

Patented July 2, 1918.

Application filed February 23, 1918. Serial No. 218,912. Term of patent 14 years.

To all whom it may concern:

Be it known that I, IGNATZ SCHWINN, a citizen of the United States, residing at Chicago, in the county of Cook and State of Illinois, have invented a new, original, and ornamental Design for a Bicycle-Frame, of which the following is a specification, reference being had to the accompanying drawing, forming part hereof.

The drawing is a perspective view of a bicycle frame, showing my new design.

I claim:

The ornamental design for a bicycle frame, as shown.

IGNAZ SCHWINN.

Witnesses:

A. C. FISCHER,
D. C. THORSEN.
